FUMIGATING SYSTEM

Arthur G. Howard, Flint, Mich.

Application June 3, 1946, Serial No. 673,999

9 Claims. (Cl. 21—108)

1

The invention relates to improvements in a system for fumigating, and more particularly to an arrangement whereby an insecticidal gas may be delivered into various equipment requiring fumigation at stated intervals and for predetermined periods of time.

The system embodying the features of the present invention is intended for use primarily in connection with the fumigation of various types of milling equipment, such as elevators, reels, purifiers, grinding rolls, packing and storage bins, and other flour or dough handling equipment. The system involves an organization including a source for generating an insecticidal gas from liquid insecticide or fumigant and a suitable system of piping for conveying the gas to various pieces of milling equipment located in different sections and on different floor levels of a building housing such equipment. Fumigation of milling equipment in particular is effected at regularly spaced intervals such as at weekly or bi-monthly periods primarily to destroy insects and incidently to eliminate the action of mold spores prevalent in flour and dough handling machinery.

It is, therefore, an object of the present invention to provide a system for fumigation, which is easy to install in new or existing mills and which is highly efficient in use and entirely automatic in its operation.

The fumigation of equipment distributed throughout various parts of a building through the operation of a centrally arranged fumigant apparatus has heretofore been inadvisable because of the difficulties involved in regulating the flow of insecticidal gas to the individual pieces of equipment, and because of the difficulties surrounding the distribution of said gas to selected pieces of such equipment. As a result, it has been common practice to separately fumigate each piece of equipment at selected intervals. However, because of the uncertainty surrounding such practice, it is preferred to provide a single apparatus operable in response to automatically actuated time control devices effective to enable fumigation of all of the equipment during operation of said apparatus, and in such manner as to insure proper fumigation of each piece of equipment connected in the system. It is, therefore, another object of the invention to provide a system of fumigation which embodies all of the desirable characteristics of the system responding to that referred to hereinabove.

Other and further objects of the present invention will be apparent from the following de-

2

scription and claims and are illustrated in the accompanying drawing which, by way of illustration, shows a preferred embodiment and the principle thereof. Other embodiments of the invention embodying the same principle may be used and structural changes may be made as desired by those skilled in the art without departing from the present invention and a purview of the appended claims.

10 In the drawing:

The figure is a schematic view showing a building in section and provided at various floor levels with different types of milling equipment commonly used for handling flour, dough, or the like, and showing the improved system of fumigation incorporated therein.

The system of fumigation illustrated in the drawing is representative of an installation organized to permit fumigation of a considerable number of pieces of different kinds of equipment found in the milling and baking industry, and it includes a single apparatus for generating insecticidal gas and automatic time control means actuatable to place various sections of the system in direct communication with the apparatus during certain periods of apparatus operation so as to thereby cause various groups or pieces of equipment to be fumigated in succession. This system permits a single generating apparatus of moderate size or cost to serve an entire plant, and also avoids the need for one or more portable generators movable into close association with each piece of milling equipment for fumigating that piece of equipment independently of all others.

35 In practicing the present invention, a building housing the milling or other equipment to be fumigated is suitably piped so as to enable distribution of the insecticidal gas to each piece of equipment requiring such fumigation irrespective of the location of such equipment. An example of such an installation is disclosed in the drawing wherein the building illustrated has a plurality of floor levels 11, each having one or 40 more pieces of milling equipment thereon. As examples of such equipment and the disposition thereof, conveyor equipment and reels 12 may be located on an upper floor level, purifiers 13 on another floor level, while grinding rolls 14 and storage bins 15 may be suitably arranged on other floor levels of the building. It should be understood at this time that the specific pieces of equipment shown are for purposes of illustration only and not for purposes of limiting the invention to the equipment disclosed. A single ap-

paratus, indicated generally at 16, for generating insecticidal gas from a liquid insecticide and which may be of a kind shown and claimed in my copending application Ser. No. 674,000, filed June 3, 1946, is arranged on the lowermost floor level and a standpipe 17 extends from said apparatus upwardly through the various floor levels to adjacent the ceiling of the uppermost floor level. The standpipe may, of course, include branches or extensions leading to other sections of the building and containing equipment other than that illustrated in the drawing, which branches or extensions are not necessary to a complete disclosure of the invention described herein.

A plurality of distribution lines, 18, 19, 21, and 22, are connected into the standpipe 17 to receive fumigant gas flowing through the standpipe during certain periods of generator operation. The distribution lines normally are shut off from the fumigant gas contained within the standpipe 17 so that any condensate that may accumulate therein will flow in the direction of said standpipe. To facilitate the drainage of condensate from each of the distribution lines 18 through 22, inclusive, said lines are each provided with a bleed conduit 21 having a check-valve 28 therein to prevent the flow of insecticidal gas therethrough. The check-valves, however, permit condensate to flow from the respective distribution lines into the standpipe 17 when the generating apparatus 16 is not in operation.

Each of the distribution lines 18 through 22, inclusive, is provided with a plurality of outlets each having a conduit 29 connected thereto. The conduits 29 may extend upwardly through the respective floor levels 11, or downwardly if the distribution line is adjacent the ceiling, and are provided at their discharge ends with dispensing valves 31 communicating with the interior of the selected piece of milling equipment with which it is associated. Thus, each piece of milling equipment 12, 13, 14 or 15, is directly connected with one of the distribution lines 18 through 22, inclusive, by means of one of the conduits 29.

A time control unit 32 is connected in the electrical circuit to the generating apparatus 16 which unit may be of any conventional construction embodying switch mechanisms adapted to hold selected circuits closed for predetermined periods of time and capable of being manually or automatically actuated to initiate operation of the system. The time control unit 32 is connected electrically to each of the solenoid valves 23, 24, 25, and 26, and is so constructed that when in operation it will successively open and then close the solenoid valves. In the present installation, starting of the time control unit manually, or in response to clock control mechanism, initiates operation of the generator apparatus 16 and also opens the solenoid valve 26 provided in the distribution line 22. The solenoid valve 26 will remain open for a time interval depending upon the setting of the control unit, during which interval insecticidal gas generated in the apparatus 16 and delivered under pressure into the standpipe 17 will flow into the distribution line 22 and its conduits 29 for discharge into the interior of the reels 12.

It has been found that a period of operation approximating one hour is sufficient to deliver the required amount of insecticidal gas to the reels 12 for combating insect growth therein. At the conclusion of this or other predetermined pe-

riod of operation, the time control unit 32 operates to open the valve 25 in the distribution line 21 and close the solenoid valve 26 in the distribution line 22. Insecticidal gas flowing through the standpipe 17 then is delivered into said line 21 and through the conduits 29 connected therewith for discharge into the purifiers 13. After a sufficient quantity of insecticidal gas has been delivered to the purifiers 13, the time control unit 32 again operates to open the solenoid valve 24 in the distribution line 19 and close the solenoid valve 25, whereupon insecticidal gas is delivered to the grinding rolls 14. When the fumigation of the grinding rolls is completed, the time control unit 32 again operates to open the valve 23 in the distribution line 18 for delivering insecticidal gas into the storage bins 15, at which time the solenoid valve 24 is closed. At the conclusion of the operating period necessary to fumigate the storage bins 15 the time control unit again operates to shut down the generating apparatus 16 and then close the valve 23.

It should be quite evident from the foregoing description that all of the equipment in a mill requiring treatment with insecticidal gas at pre-determined intervals is fumigated through the operation of a single generating unit by means of the present system of fumigation. In this manner, a single unit may accommodate a large number of pieces of equipment, some of which are treated for a required period of time before other pieces of equipment are successively cut into the system for treatment, and that any condensate accumulating in the distribution lines 18 through 22, inclusive, will return to the standpipe 17 and to the generating apparatus 16 following shut down of the system.

It should be understood further that although an exemplary installation has been disclosed in the accompanying drawing and described in detail in the foregoing specification, the system may include other and additional equipment than that shown, and may be installed in buildings having such equipment located on different floor levels or upon a single floor level. In the latter instance, various pieces or groups of equipment will be independently piped through main distribution lines from the standpipe 17 or other header, and each of such lines will have an electrically controlled valve therein electrically connected with the time control unit so that said valves may be opened and closed in succession to thereby avoid overloading the generating apparatus 16.

I claim:

1. In a system for fumigating which comprises an apparatus for generating insecticidal gas, a standpipe through which said insecticidal gas is delivered, a plurality of distribution lines connected into said standpipe, a normally closed valve in each distribution line, and means actuatable to initiate operation of the generating apparatus and to open and close said valves in succession so as to successively place each distribution line in communication with the standpipe for predetermined periods of time.

2. In a system for fumigating which comprises an apparatus for generating insecticidal gas, a standpipe through which said insecticidal gas is delivered, a plurality of distribution lines connected into said standpipe, a normally closed valve in each distribution line, means actuatable to initiate operation of the generating apparatus and to open and close said valves in succession

so as to successively place each distribution line in communication with the standpipe for predetermined periods of time, and a by-pass in each distribution line effective to bleed said line when the generating apparatus is shut down.

3. In a system for fumigating which comprises an apparatus for generating insecticidal gas, a standpipe through which said insecticidal gas is delivered, a plurality of distribution lines connected into said standpipe, a normally closed valve in each distribution line, means actuatable to initiate operation of the generating apparatus and to open and close said valves in succession so as to successively place each distribution line in communication with the standpipe for predetermined periods of time, and a by-pass in each distribution line effective to bleed said line when the generating apparatus is shut down, said means being effective to shut down the generating apparatus when the last distribution line valve is closed.

4. In combination with a building structure having a plurality of floor levels and equipment to be fumigated on each level, a generator for an insecticidal gas located on a lower floor level of such structure, a standpipe extending from said apparatus, distribution lines communicating with said standpipe one at each floor level, and a plurality of conduits connecting each distribution line with equipment located on said level.

5. In combination with a building structure having a plurality of floor levels and equipment to be fumigated on each level, a generator for an insecticidal gas located on a lower floor level of such structure, a standpipe extending from said apparatus, distribution lines communicating with said standpipe one at each floor, a plurality of conduits connecting each distribution line with equipment located on said level, and a dispensing valve in each of said conduits.

6. In combination with a building structure having a plurality of floor levels and equipment to be fumigated on each level, a generator for an insecticidal gas located on a lower floor level of such structure, a standpipe extending from said apparatus, distribution lines communicating with said standpipe one at each floor level, means op-

erable to initiate operation of the generator, said means being effective to place said distribution lines in communication with the standpipe during apparatus operation and to shut down the apparatus after a predetermined period of operation, and a plurality of conduits connecting each distribution line with equipment located on said level.

7. A system for fumigating which comprises a source of fumigant gas, a standpipe through which said fumigant gas may flow, a plurality of distribution lines connected into said standpipe, a normally closed solenoid valve in each distribution line, means operable to actuate said valves in timed sequence so as to successively open and after a predetermined time close said valves, conduits connecting said distribution lines with the equipment to be fumigated, and dispensing valves in said conduits.

8. A system for fumigating which comprises an apparatus for generating fumigant gas, a standpipe through which said fumigant gas may flow, a plurality of distribution lines connected into said standpipe, a normally closed solenoid valve in each distribution line, means operable to actuate said valves in timed sequence so as to successively open and after a predetermined time close said valves, and conduits connecting said distribution lines with the equipment to be fumigated.

9. In a system for fumigating which comprises an apparatus for generating insecticidal gas, a standpipe through which said insecticidal gas may be delivered, a plurality of distribution lines connected into said standpipe, a normally closed valve in each distribution line, means actuatable to initiate operation of the generating apparatus and to open and close said valves in succession so as to successively place each distribution line in communication with the standpipe for predetermined periods of time, and means by-passing each valve effective to enable condensate in each distribution line to flow into the standpipe when the valve is closed and the generating apparatus is shut down.
